Fig.-5

Fig.-3

Fig.-4

Figure 1 is a top view of the windshield wiper arm showing my new design;

Figure 2 is a side view in elevation of the arm illustrated in Figure 1;

Figures 3 and 4 are respectively taken on lines 3—3 and 4—4 of Figure 2; and

Figure 5 is an enlarged fragmentary perspective view of the full line portion of the wiper arm.

The dotted lines showing in Figures 1 and 2 are for illustrative purposes only.

The dominant feature of my design resides in the full line portion of the drawing.

I claim:

The ornamental design for a windshield wiper arm, substantially as shown and described.
